UNITED STATES PATENT OFFICE.

FREDERICK A. THOMANN, OF EAST MOLINE, ILLINOIS, ASSIGNOR TO DEERE & COMPANY, OF MOLINE, ILLINOIS, A CORPORATION OF ILLINOIS.

FLASK FOR CASTING METALLIC-WHEEL HUBS.

Application filed September 22, 1924. Serial No. 738,990.

My invention relates to metallic wheels and particularly to that type in which the tire is cast upon the spokes after the latter and the tire have been assembled. The object of my 5 invention is the production of a complete wheel with an economy of metal in the hub without a sacrifice of strength and efficiency.

Referring to the drawings in which similar numerals indicate identical parts—

10 Figure 1 is a side elevation of a flask ready for a casting with the wheel spokes in place therein.

Figure 2 is a section on the line 2—2 of Figure 1 and showing part of a wheel tire 15 and spokes connected therewith.

Figure 3 is a fragmentary view of Figure 1, the sprue hole and the relative position thereto of part of my improvement.

Figure 4 is a section on the line 4—4 of 20 Figure 2.

Figure 5 is a plan view of part of my improvement, and

Figure 6 is a fragmentary view of the position of the spoke ends in the flask before 25 pouring.

The flask is preferably cylindrical in outward form and is of a type known in the art; it is composed of parts 1 and 2, the part 1 having a series of fingers 3 which register 30 with similar fingers 4 on the part 2 when the parts are together. Either of the parts, part 1 in this instance, is provided with a sprue hole 5. The inner conformation of the flask is that of the article to be cast, in this instance the hub of a metallic wheel. Lugs 6 and 7 are diametrically opposite on the part 2 and are preferably integral therewith, similar lugs 8 and 9 are on the part 1. Between the lugs 6, on the part 2, is pivotally 40 secured, by a suitable bolt, an arm 10, and a similar arm 11 is secured in the same manner between the lugs 7; the arm 10 is adapted to be inserted between the lugs 8 on the part 1 and is provided with a slot 12. The arm 45 11 is adapted to be received between the lugs 9 and is provided with a slot 13; wedges are employed in the slots 12 and 13 to hold the parts 1 and 2 firmly together, and it is readily apparent that by removing the wedges 50 the parts 1 and 2 are easily separated.

Each of the fingers 3 and 4 has a groove 14 in the end thereof which registers with a similar groove 15 between the fingers 3 and 4 respectively, these grooves are for reception 55 of the hub ends of the wheel spokes and con-

sequently are radial to the axis of the wheel for which the hub is to be cast, and while the cast is being made the spokes are held rigidly in the grooves and project into the flask the necessary distance to be caught by the flowing metal. The spokes 16 are first riveted to the rim or tire 17, and are staggered and provided respectively with a button 18 on their free ends. The parts 1 and 2 of the flask being separated the spokes 16 are laid 60 in the grooves in the part 2, a sand core 19 is inserted for the axle bearing and the part 1 of the flask is joined to the part 2 and the parts are held together rigidly as previously explained. If the cast is made at 65 this time the hub will contain an excess of metal axially between the staggered spokes, more metal than is necessary for the working strain to which the wheel may be subjected, and to save this excess metal, I employ a cast ring, formed of parts 20 and 21, which fits within the flask and is inserted 70 therein after the ends of the spokes are placed and before the parts of the flask are assembled.

The sprue hole 5 necessitates the omission of a finger 3 on the part 1, and to hold the spoke, which would otherwise be held by a finger, I provide a lug 22, integral with the part 21 of the ring and adapted to contact 75 with adjacent fingers 4 of the part 2, the lug 22 serving to hold the spoke at that particular point and to prevent a rotary movement of the ring in the flask. Both parts of the ring are cut away at *a* to provide a gate 80 23 through which the molten metal passes into the flask.

When a casting is made, with the ring omitted, the result is a hub of the usual and common form, but by employing the ring 95 there is a material decrease in the amount of metal in the hub, and a circumferential groove is formed in the hub, substantially central of the length thereof, where there would be solid metal if the ring was not employed. The device has proven of great economy in the construction of wheels of this class, without sacrifice of strength and efficiency.

What I claim is—

1. A sectional flask for molding wheel hubs having its interior conforming to the shape of a hub, spoke holes in said flask, a sectional ring fitting snugly within the flask, a core 100 extending through said ring and supported 110

in the flask and having a lesser diameter than the inner diameter of the ring, and means to hold said ring in position.

2. A flask for molding wheel hubs composed of sections adapted to be secured together and having its interior conforming to the shape of a hub, spoke holes in said flask, a two part ring fitting snugly within the flask, a core extending through said ring and supported in the flask and spaced apart from the inner surface of the ring, and a lug on one part of said ring engaging with a part of said flask whereby said ring is held from rotary or lateral movement.

15 3. A flask for molding wheel hubs com-

posed of sections adapted to be secured together and having its interior conforming to the shape of a hub, spoke holes in said flask, a two part ring fitting snugly within the flask, a core extending through said ring and supported in the flask and spaced apart from the inner surface of the ring, a lug on one part of said ring engaging with a part of said flask, and operating, to hold the ring from rotary or lateral movement, a sprue in one part of the flask, and a gate in said ring leading from the sprue to the interior of the flask.

FREDERICK A. THOMANN.
